UNITED STATES PATENT OFFICE.

EDWARD B. GIBFORD, OF ADRIAN, MICHIGAN.

PARING-KNIFE.

No. 891,925.

Specification of Letters Patent.

Patented June 30, 1908.

Application filed August 23, 1907. Serial No. 389,860.

To all whom it may concern:

Be it known that I, EDWARD B. GIBFORD, citizen of the United States, residing at Adrian, in the county of Lenawee and State 5 of Michigan, have invented certain new and useful Improvements in Paring-Knives, of which the following is a specification.

This invention relates to paring knives, and has for its object to provide an improved 10 knife which can be used as a parer, an eye cutter, and a scraper, for various fruits and vegetables.

The implement embodies a blade which is separate from its holder, the former being 15 formed of hard or razor steel, and the latter being more cheaply and conveniently produced in softer metal, and capable of being stamped out of a blank and bent in proper shape to hold the blade in place.

20 The invention is illustrated in the accompanying drawing, in which,

Figure 1 is a plain view of the knife. Fig. 2 is a front edge view of the knife. Fig. 3 is a bottom or inverted plan view. Fig. 4 is a 25 section on the line 4—4 of Fig. 1. Fig. 5 is a cross section through the handle. Fig. 6 is a plan view of the blank from which the blade holder is made.

Referring specifically to the drawing, the 30 blade of the knife is indicated at 6, and this consists of a thin piece of hard or razor steel sharpened along one edge. This blade is held in a holder formed from the blank shown in Fig. 6. This holder may be conveniently 35 made of galvanized iron or other sheet metal. Said blank is folded lengthwise to form an upper leaf or part 7 and a lower leaf or part 8, the blade being held between these parts, sufficient pressure being applied to hold the 40 blade firmly in place. At the rear edge the blade backs against the bend or crease of the holder, as indicated at 9.

The top leaf or part 7 is provided near its front edge with a longitudinal slot 10 and the 45 width of the blade is such that its cutting edge is located directly under this slot and projecting part-way across the same, so that the peelings or slices of the fruit or vegetable are cleared from the knife through the slot.

50 The front edge of the upper part 7 projects out beyond the cutting edge of the knife and is turned or bent outwardly from the plane of the blade as shown at 11, forming a guard

and also a gage for the edge of the blade. It acts as a guard because it projects beyond 55 the cutting edge of the blade and prevents accidental contact therewith, and it acts as a gage to limit the depth of the slices or cut because in the act of cutting the outturned lip will come into contact with the surface of the 60 article being cut and thus hold the knife to a uniform depth. At its outer end the top of the holder is provided with a lip 12, which is turned outwardly from the plane of the blade and beveled at the edge to form an eye cut- 65 ter for use particularly with potatoes.

The holder above described is provided with a handle 13, the blank forming the holder having a shank 14, which is doubled or folded and driven into the handle. This 70 folded construction of the shank insures great strength and rigidity and serves to prevent the holder being broken off at the shank, under any ordinary strain. The handle has a ferrule 15 which is notched as at 16, and 75 this notch receives a shoulder 17 formed at the junction of the body and shank of the holder. The engagement of the shoulder and notch prevents the holder from turning in the handle.

Should the blade become broken or worn out it is possible to substitute another blade, by forcing the old blade out and the new blade in, this action being effected by sliding the same in or out lengthwise. The advan- 85 tage of having the separate blade is that it may be made from hard and thin metal, which is not conveniently possible in knives in which the whole knife is made in one piece. The turned edge 11 at the front of the holder 90 may be used as a scraper for removing the skins of new potatoes and the like.

I claim:—

A knife comprising a blade, a holder there- 95 for, and a handle, the holder consisting of a sheet metal blank folded lengthwise, with the blade held between the fold, the upper part of the holder being slotted above the edge of the blade and having an extended lip turned outwardly in front of said slot.

In testimony whereof I affix my signature, in presence of two witnesses.

EDWARD B. GIBFORD.
